UNITED STATES PATENT OFFICE.

ADOLPH PETER GUSTAFSON, OF CHICAGO, ILLINOIS, ASSIGNOR TO M. SCHULZ CO., OF CHICAGO, ILLINOIS.

CONTROLLER-LEVER FOR AUTOMATIC MUSICAL INSTRUMENTS.

1,136,955.

Specification of Letters Patent. Patented Apr. 27, 1915.

Application filed December 4, 1913. Serial No. 804,612.

To all whom it may concern:

Be it known that I, ADOLPH P. GUSTAFSON, a citizen of the United States, residing at Chicago, in the county of Cook and State of Illinois, have invented a certain new and useful Improvement in Controlling-Levers for Automatic Musical Instruments, of which the following is a full, clear, concise, and exact description, reference being had to the accompanying drawings, forming a part of this specification.

My invention relates to controlling levers for automatic musical instruments, such for example as player pianos, and the like.

Prominent objects of my invention are to provide a simple, practical and effective construction of controlling device of the kind specified; to permit the same to be easily placed in position for operation and removed from such position out of the way; to avoid cutting or changing the instrument in order to accommodate the levers; and to secure the foregoing and other desirable results in a simple and expeditious manner.

In the accompanying drawings Figure 1 is an elevation of a portion of a player piano, having controlling levers embodying my invention; Fig. 2 is a vertical section taken on line 2-2 in Fig. 1; Fig. 3 is a side elevation of one of the members, and Fig. 4 is a plan of a portion of the same.

In the drawings I show a portion of a player piano comprising the part 1, key-bed 2 and keys 4-4.

Controlling levers 5-5 are shown for controlling the various instrumentalities of the instrument. These levers preferably are arranged to stand in front of the key-rail 2 when in use and to be lowered so as to be out of the way when not in use. As a simple and advantageous construction for this purpose I show said levers 5 conveniently made in the form of an L having a long bar or arm 5^a, and a short cross bar 5^b, which latter is pivoted at 6, so as to permit said lever to be swung down as shown in dotted lines in Fig. 2. Thus when in an upright position as shown in Fig. 2, the lever is available for service and may be swung or moved as desired in accordance with its connections or arrangements to operate the device or instrumentality which it is intended to control. When, however, the use of the instrument is discontinued, said lever 5 may be

and will then come into position as shown in dotted lines in Fig. 2, conveniently under the key rail 2 and behind the front edge of the same, so that said lever is completely out of the way. The lever 5 is shown pivoted to a rod or bar 7 to illustrate one form of connection which may be made with said lever 5, in which case the pivot 6 pivots the arm 5^b to said rod or bar 7. The rod or bar 7 is shown extending back toward the rear of the instrument where it is understood to be connected in some suitable or proper way with an instrumentality which it is to control. The arm 5^b of the lever 5 is desirably provided with a notch 8 and the rod or bar 7 with a pin 9 which is adapted to fit the notch 8 so as to serve as a stop for the lever 5 and limit the forward movement thereof. The pivot 6 is preferably arranged in connection with a strong spring or strap 10 which is secured to the bar 7 by a rivet 11, and engages the outer end of the pivot 6 so as to hold the head thereof strongly against the arm 5^b, and thereby permit said arm to be held firmly against the bar 7 so as to permit the lever 5 to be properly swung up and down into and out of position but at the same time to provide friction enough to hold said lever in any position to which it may be adjusted.

It will be seen that when the levers are up in position they allow easy and proper manipulation to bring about the desired control of the instrument, and when swung down said levers are well out of the way, and this is accomplished without cutting the front parts of the instrument or providing any covers or similar devices to cover up the levers.

It will be understood that changes and modifications may be made without departing from the spirit of the invention.

What I claim is:

1. In an instrument of the class specified, the combination of a movable member for use in the operation of the instrument, a controlling lever pivoted to said member, and means for exerting friction upon the pivotal connection between said member and lever.

2. In an instrument of the class specified, the combination of a movable member for use in the operation of the instrument, a controlling lever pivotally mounted upon said member, and a spring exerting tension on said pivotal mounting to cause friction at the same.

- 2
3. In an instrument of the class specified, the combination of a movable member for use in the operation of the instrument, a lever pivoted to said member, a pivot forming the pivotal connection between said lever and member, and a spring connected with one end of said pivot and arranged to draw upon the same so as to cause friction at said pivotal connection.
- 10 4. In an instrument of the class specified, the combination of a movable member for use in the operation of the instrument, a lever pivotally connected with said member, and a pin carried by said member, said lever having a notch adapted to engage said pin to limit the extent of pivotal movement of said lever.
- 20 5. In an instrument of the class specified, the combination of a movable member for use in the operation of the instrument, said member extending in a forwardly and rearwardly direction, and having its front end at the front of the instrument, a controlling lever for manual engagement pivotally connected with the front end of said movable member, and spring means exerting tension
- 25
5. In an instrument of the class specified, the combination of a movable member for use in the operation of the instrument, said member extending in a forwardly and rearwardly direction, and having its front end at the front of the instrument, a controlling lever for manual engagement pivotally connected with the front end of said movable member, and spring means exerting tension
- upon the pivotal connection between said member and lever tending to hold the latter in the position to which it is adjusted.
6. In an instrument of the class specified, 30 the combination of a movable member for use in the operation of the instrument, said member extending in a forwardly and rearwardly direction, and having its front end at the front of the instrument, a controlling 35 lever for manual engagement pivotally connected with the front end of said movable member, and spring means exerting tension upon the pivotal connection between said member and lever tending to hold the latter 40 in the position to which it is adjusted, said spring means comprising a flat spring having one of its ends secured to said member and its other end secured to the pivot forming said pivotal connection.

In witness whereof, I hereunto subscribe my name this 17th day of November, A. D., 1913.

ADOLPH PETER GUSTAFSON.
